UNITED STATES PATENT OFFICE.

HOWARD DOUGLAS HODGE, OF WALTHAM ABBEY, ENGLAND, ASSIGNOR TO NOBEL'S EXPLOSIVES COMPANY, LIMITED, OF GLASGOW, SCOTLAND.

CARTRIDGE-MAKING MACHINE.

937,604.

Specification of Letters Patent. Patented Oct. 19, 1909.

Application filed January 9, 1909. Serial No. 471,442.

To all whom it may concern:

Be it known that I, HOWARD DOUGLAS HODGE, works manager of Waltham Factory, Nobel's Explosives Co., Ltd., a citizen of the 5 United States, residing at Joyce House, Waltham Abbey, Essex, England, have invented a new and useful Improved Cartridge-Making Machine, of which the following is a specification.

10 The object of this invention is to provide an improved cartridge making machine especially suitable for inserting the primers into the shells or cases.

15 In a machine constructed in accordance with this invention the cartridge shells are fed head downward to a rocking segment or arm which inverts them by turning them around a point on the edge of their rims and drops them down onto supports or pins 20 standing up from a horizontal wheel which is rotated step by step. A reciprocating carrier above the wheel is provided with the various punches for inserting the primers which are delivered to the shells by means of 25 fingers on a rocking shaft.

A machine embodying my invention is illustrated in the accompanying drawings in which—

Figure 1 is a plan and Fig. 2 a side elevation, these two figures being to a small scale. Figs. 3 and 4 are sectional elevations at right angles to Fig. 2. Fig. 5 is a plan, Fig. 6 an end view and Figs. 7 to 10 are detail views of the mechanism for inverting the 30 shell. Fig. 11 is a sectional plan showing how certain of the parts are actuated. Fig. 12 is a plan of the stop mechanism. Fig. 13 is a section on the line A—A Fig. 11. Fig. 14 shows a detail. Fig. 15 is a diagrammatic 40 view of an electric alarm. Fig. 16 shows a detail.

a is the main shaft provided with fast and loose belt pulleys and carrying a rope pulley a¹ from which a rope a² passes to a pulley a³ 45 on a second shaft a⁴ which by bevel gear a⁵ (see Fig. 4) drives a vertical spindle a⁶ from which a rope a⁷ drives the vertical shaft b¹ of a horizontal disk b adjacent to a fixed table b² upon which the shells 1 are placed.

50 Owing to the weight of their heads they may be readily placed in a vertical position with their heads downward upon this table which may be slightly inclined so that they can be the more readily pushed onto the

disk b which in its rotation carries them 55 around to the funnel shaped mouth of a guide way b³ near which mouth may be situated an irregularly toothed wheel b⁴ rotated by a rope drive b⁵ (see Figs. 1 and 4) in the same sense as the disk so as to move back some of 60 the shells and prevent jamming. Shells which get too near the center of the disk to enter the guide way are carried around until they meet an inclined fence b⁶ which causes 65 them to move out toward the circumference 70 of the disk so that they may enter the guide as they again come around. The guide narrows down until there is only room for one shell to pass at a time and the shells are thus fed one by one head down- 75 ward onto a platform c (see Figs. 5 and 6.) Any further movement to which the shell may have been prone owing to the pressure of the shells behind is now prevented by a fixed wall c¹.

d is a segment carried by a bracket d¹ fast on a rocking shaft d² having on it friction collars d³ between which is gripped a pinion d⁴ gearing with a rack d⁵ which receives a vertical reciprocating movement from a 80 yoke d⁶ on a cam d⁷ on the shaft a. The friction collars allow slip to take place should a shell get jammed. On the shaft d² is an arm d⁸ which comes against adjustable stops d⁹ (see Fig. 7 which is a section on the 85 line 7—7 Fig. 5) by which the angle through which the shaft is rocked by the reciprocating rack can be accurately defined. The segment d has on it a piece d¹⁰ which, as the segment rocks, comes against the open end 90 of the shell 1 and turns it over, the head of the shell being temporarily retarded by a stop c² on the platform c. The segment d thus comes in front of the foremost shell of the column in the guide way and prevents 95 further movement thereof until the segment has returned to its back position when another shell is pushed out onto the platform c. The shell is thus by the movement of the segment, turned about a point on the edge of 100 its rim or about the stop c² and inverted, the piece d¹⁰ being curved at d¹¹ in order that it may not catch against the rim of the head (see Fig. 6). This movement of the shell is also controlled by a flange c³ on the wall c¹. 105 As soon as the head of the shell has turned around the stop c² a presser foot e working in a slot c⁴ in the wall c¹ comes down upon

the head and presses the shell down onto one of a number of pins f standing up from the face of a wheel f^1 .

On a connecting rod a^8 from cranks a^9 on the shaft a is a tool carrier g which slides in vertical guides g^1 and pivoted to which at e^1 is a lever fulcrumed at one end on the frame at e^2 while its other end is linked by a link e^3 to the top of the stem e^4 of the presser foot e , so that every time the carrier g descends, that is once every revolution of the shaft a , the presser comes down and presses a shell down onto a pin f . At the bottom of the wall e^1 are two spring stops e^5 upon which the shell rests until the pressure of the foot e forces it past them.

A step by step movement of rotation is imparted to the wheel f^1 as follows:—A lever f^2 (see Fig. 2) fulcrumed on the frame at f^3 is rocked by a crank pin f^4 on the main shaft a and by means of a link f^5 moves a slide f^6 to and fro in horizontal guides f^7 . To this slide is pivoted a pawl f^8 (see Fig. 11) adapted to engage recesses f^9 cut on the periphery of the wheel f^1 , a spring f^{10} bringing the pawl into engagement. The wheel is pressed down onto the bed of the machine by a friction spring f^{11} which prevents backlash. Should it be preferred to insert the anvil and primer separately, the anvil is now inserted by the operator. As the wheel rotates the shell comes beneath an inspecting punch or arm h sliding in the carrier g . This punch is so set that the head of a cartridge prevents it from moving with the carrier for the last part of the travel thereof but should a pin upon which no shell has been placed stop beneath the punch h , there is nothing to arrest the movement of the punch and a lug h^1 upon it comes against a segment i (see Fig. 3) and turns it on its pivot i^1 thus pushing in a pin i^2 which in turn pushes in a lever i^3 toward the right as seen in Figs. 3 and 12 against a spring i^4 . This movement brings the lever i^3 from beneath a fixed shoulder i^5 and it is then free to rock about its pivot i^6 . Connected to this lever is a link i^7 constantly pulled upward by a spring i^8 , thus when there is no shell on a pin this link rises and moves an incline i^9 into the path of a projection i^{10} on the shaft and so disengages a clutch (not shown) and stops the machine. The machine may also be stopped when desired by the hand lever j and links j^1 connecting it to the lever i^3 . At the next two stops of the wheel f^1 the shell is beneath punches k k^1 the first of which clears and sizes the pocket in the head of the cartridge which is adapted to receive the primer while the second clears the communication hole at the bottom of such pocket. The shell now arrives at the point where the primer is inserted. The primers are placed head downward on a table l from which they are pushed

onto a disk l^1 similar to the disk b rotated by a rope drive a^{10} from the spindle a^6 . The disk feeds the primers into a guide way l^2 following which they come up against a stop l^3 which is normally held up in their path by a spring l^4 (see Figs. 13 and 14).

In order to prevent jamming of the primers at the mouth of the guideway l^2 an agitator l^5 may be carried by an arm l^6 pivoted to the frame and rocked by a cam l^7 on the shaft a^4 (see Figs. 1 and 2).

Bolted to the carrier is a vertical rack m gearing with a pinion m^1 gripped between friction collars m^2 on a shaft m^3 rocking on pivots m^4 . At m^5 two fingers m^6 are pivoted to this shaft and their tips are kept together by a spring m^7 which embraces them. The tips of these fingers are hollowed out and also beveled so that as they are brought by the rocking of the shaft into the position shown in Fig. 11 they (first pressing down the stop l^3 against the spring l^4) open slightly, pass down over and grip the primer which is waiting for them. As the rack m descends the shaft m^3 is rocked and the fingers are thus turned through two right angles and hold the primer directly over the pocket in the head of a shell, into which pocket a punch n on the carrier now pushes the primer a little way. At the next stop of the wheel a punch n^1 pushes it a little farther in, and at the next stop, a third punch n^2 pushes it home. If desired this punch n^2 may be capable of sliding a small distance in the carrier (see Fig. 15) and may have upon it a finger n^3 adapted to contact with an insulated terminal n^4 fixed to the carrier. An electric battery and a bell are connected to the frame of the machine and to the terminal n^4 . Should therefore a primer have been missed and a shell arrive beneath punch n^2 without its primer, the punch will meet with no resistance and will not move relatively to the carrier, the finger n^3 will thus come into contact with the terminal n^4 and a signal will be given to the operator. At the next stop, the shell is picked off the pin as follows:—The carrier g carries a tube o at the lower end of which are two weighted jaws o^1 (see Fig. 16) which can slide in inclined guides o^2 on the tube. As the carrier descends these jaws pass down over the rim of the head of the cartridge. As the carrier rises the jaws retain their hold of the head and the shell is thus drawn off its pin. On the next descent of the carrier the shell held in the jaws comes down onto the head of the next shell and is thus pushed up into the tube, raising any shells that may be in the tube, the top one of the column falling out of the top of the tube into a collecting receptacle. Or the tube may connect by a telescopic joint with a tube passing over the machine and dropping the shells into a receptacle placed beneath its 125

mouth. At the next step a second inspector punch p may be arranged upon the carrier to descend upon the head of the pin. Should the pickoff have failed to act and a shell have been left on the pin the downward movement of the punch is checked, the punch therefore moves relatively to the carrier and comes against one end of an arm p^1 (see Figs. 3 and 12) pivoted to the carrier at p^2 ; the other end of this arm is thus caused to press upon the segment i and the machine stops as already explained.

What I claim is:—

1. In a cartridge making machine, the combination of a platform, and means for turning around a point on the edge of its rim and inverting a shell placed head downward upon the platform.
  2. In a cartridge making machine, the combination of a platform, means for inverting a shell placed head downward upon the platform, and means for retarding the movement of the head of the shell.
  3. In a cartridge making machine, the combination of a platform, means for inverting a shell placed head downward upon the platform, and a stop upon the platform adapted to retard the movement of the head of the shell.
  4. In a cartridge making machine, the combination of a platform, a segment adapted to engage a shell placed head downward upon the platform, means for rocking the segment, and means for retarding the movement of the head of the shell.
  5. In a cartridge making machine, the combination of a platform, means for feeding shells one by one head downward upon the platform, a segment adapted to engage a shell when in position upon the platform, means for rocking the segment, and means for retarding the movement of the head of the shell.
  6. In a cartridge making machine, the combination of a platform, means for feeding shells one by one head downward upon the platform, a fixed wall beyond the platform, a curved flange upon the wall, a segment adapted to engage a shell when in position upon the platform, and means for rocking the segment.
  7. In a cartridge making machine, the combination of a platform, a horizontal wheel rotating below the platform, pins standing up from the surface of the wheel, means for inverting a shell placed head downward upon the platform, means for retarding the movement of the head of the shell, and means for placing it upon one of the pins.
  8. In a cartridge making machine, the combination of a guideway, a horizontal disk adapted by its rotation to carry shells placed head downward upon it into the guideway, means for rotating the disk, a platform at the end of the guideway, a segment adapted to engage a shell when in position upon the platform, means for rocking the segment, a stop upon the platform adapted to retard the movement of the head of the shell, a horizontal wheel rotating below the platform, pins standing up from the surface of the wheel, a presser adapted to engage the head of the inverted shell and press it down upon one of the pins, and means for reciprocating the presser.
- the end of the guideway, a segment adapted to engage a shell when in position upon the platform, means for rocking the segment, means for retarding the movement of the head of the shell, a horizontal wheel rotating below the platform, pins standing up from the surface of the wheel, a presser adapted to engage the head of the inverted shell and press it down upon one of the pins, and means for reciprocating the presser.
9. In a cartridge making machine, the combination of a guideway, a horizontal disk adapted by its rotation to carry shells placed head downward upon it into the guideway, an irregularly toothed wheel situated at the mouth of the guideway, means for rotating the disk and wheel, a platform at the end of the guideway, a segment adapted to engage a shell when in position upon the platform, and means for rocking the segment.
10. In a cartridge making machine, the combination of a guideway, a horizontal disk adapted by its rotation to carry shells placed head downward upon it into the guideway, an irregularly toothed wheel situated at the mouth of the guideway, means for rotating the disk and wheel, a platform at the end of the guideway, a segment adapted to engage a shell when in position upon the platform, means for rocking the segment, a horizontal wheel rotating below the platform, pins standing up from the surface of the wheel, a presser adapted to engage the head of the inverted shell and press it down upon one of the pins, and means for reciprocating the presser.
11. In a cartridge making machine, the combination of a guideway, a horizontal disk adapted by its rotation to carry shells placed head downward upon it into the guideway, means for rotating the disk, a platform at the end of the guideway, a fixed wall beyond the platform, a curved flange upon the wall, a segment adapted to engage a shell when in position upon the platform, means for rocking the segment, and a stop upon the platform adapted to retard the movement of the head of the shell.
12. In a cartridge making machine, the combination of a guideway, a horizontal disk adapted by its rotation to carry shells placed head downward upon it into the guideway, means for rotating the disk, a platform at the end of the guideway, a fixed wall beyond the platform, a curved flange upon the wall, a segment adapted to engage a shell when in position upon the platform means for rocking the segment, a stop upon the platform adapted to retard the movement of the head of the shell, a horizontal wheel rotating below the platform, pins standing up from the surface of the wheel, a presser adapted to engage the head of the inverted shell and press it down upon one of the pins, and means for reciprocating the presser.

13. In a cartridge making machine, the combination of a platform, a horizontal wheel rotating below the platform, pins standing up from the surface of the wheel, 5 means for inverting a shell placed head downward upon the platform, placing it upon one of the pins, a tool carrier above the wheel, a series of punches carried by the carrier and adapted to insert a primer into the head of the shell, means for reciprocating 10 the carrier, an inspecting punch on the carrier, and trip mechanism adapted to be actuated by the punch to stop the machine.

HOWARD DOUGLAS HODGE.
